JAMES M. JACKSON

by Arthur W. Harrison
Attorney

UNITED STATES PATENT OFFICE.

JAMES MARION JACKSON, OF MILLPORT, NEW YORK, ASSIGNOR TO MYRA K. JACKSON, OF SAME PLACE.

CHURN.

SPECIFICATION forming part of Letters Patent No. 530,531, dated December 11, 1894.

Application filed April 14, 1894. Serial No. 507,546. (No model.)

To all whom it may concern:

Be it known that I, JAMES MARION JACKSON, a citizen of the United States, residing at Millport, in the county of Chemung and State of New York, have invented certain new and useful Improvements in Churns; and I do hereby declare the following to be a full, clear, and exact description of the invention, such as will enable others skilled in the art to which it appertains to make and use the same.

My invention relates to churning and has particular reference to that type of such machines in which the dasher is mounted on a horizontal axis and within a drum-shaped or cylindrical casing.

The object of my invention is to provide means whereby wear of the bearings can be taken up and yet permit no escape of the cream at such bearings; and a further object of my invention is to provide a light, simple and economically constructed churn.

To these ends my invention consists in the construction and combination of parts as hereinafter described and claimed.

In the accompanying drawings, Figure 1 is a side elevation of the churn. Fig. 2 is a section on line 2—2 of Fig. 1. Fig. 3 is a detail perspective of a portion of the dasher frame. Fig. 4 is a detail section illustrating a modification hereinafter referred to.

Similar reference letters indicate the same parts in the several views.

The cylindrical or drum-shaped casing *a* is mounted on a suitable base *a'*; and secured in the center of one of the heads *a*² is a screw-threaded bushing *b*, through which extends the screw *b'* having its inner end preferably rounded as shown. A set-nut *b*² is employed to hold the screw in its adjusted position and a washer *b*³ is interposed between the said nut and the flange of the bushing to make this bearing liquid tight. The other head *a*³ of the casing has centrally secured therein an inwardly flaring cone-shaped thimble or bearing *c* in which is fitted the cone plug *c'* having a screw-threaded stud at its outer end and a square stud *c*² at its inner

end. A crank handle *d* is secured upon the outer end of the plug. 50

The dasher frame consists of the side pieces or arms *e* and the paddles or dashers proper *e'*, the former being cut out at their ends to a width less than the thickness of the latter, as shown at *e*² in Fig. 3, and said dashers being provided with rabbets so that they may be slipped into the ends of the arms and there held by one or more pins *c*³, preferably of wood. One of the side pieces *e* is provided at its middle with a concaved socket piece *f* 60 to receive the end of screw *b'*, and the other side piece is provided with a square socket *f'* to receive the square stud *c*² of the plug *c'* so that the dashers may be operated by the handle *d*. 65

To take up wear of the bearings, the nut *b*² is loosened, the screw *b'* turned to cause the dasher frame to press the cone-plug well into its bearing *c*, and the nut again tightened.

The close fit of the plug and bearing prevents rattling or leakage at that end of the casing, while at the other end, the concaved socket *f* prevents rattling and the washer *b*³ prevents leakage. 70

The screw *b'* and socket *f* may be of wood, 75 and the socket *f'* and plug *c'* may also be of wood, thus avoiding the use of any metal in the churn. In this case the thimble *c* is dispensed with, as indicated in Fig. 4, and the conical bearing in the casing elongated by 80 securing on the outside thereof a block *c*¹⁰.

The opening of the casing at the top is provided with a funnel shaped mouth *g* in which the square cover *g'* having beveled sides *g*² fits. 85

Owing to the dashers being at the ends only of the frame, when the cream has been agitated sufficiently to produce the granules of butter, the lower dasher can be reciprocated back and forth in the mass (the upper one 90 being above the surface) and so gather the butter.

Having now described my invention, what I claim is—

1. A churn comprising in its construction 95 a casing having a fixed cone-shaped bearing

at one end and a screw at the other end, a cone-plug fitted in said bearing whereby a tight joint is formed between the casing and the cone-plug, and a dasher frame mounted 5 on said screw and cone-plug, substantially as described.

2. A churn comprising in its construction the casing having the screw b' nut b^2 and washer b^3 at one end, and the hollow cone c 10 at the other end, the cone-plug c' having a

handle and the square stud c^2 , and the dasher frame having the concave socket f and the square socket f' , substantially as described.

In testimony whereof I affix my signature in presence of two witnesses.

JAMES MARION JACKSON.
